US0D1077686S

(12) **United States Design Patent** (10) **Patent No.:** **US D1,077,686 S**
(45) **Date of Patent:** **** Jun. 3, 2025**

(54) **ELECTRIC BICYCLE**

(71) Applicant: **Guangzhou Enffe Technology Co., Ltd.**, Guangdong (CN)

(72) Inventor: **Huipeng Chen**, Jiangxi (CN)

(**) Term: **15 Years**

(21) Appl. No.: **29/997,218**

(22) Filed: **Apr. 7, 2025**

(51) LOC (15) Cl. **12-11**

(52) U.S. Cl.

USPC **D12/111**

(57)

CLAIM

The ornamental design for an electric bicycle as shown and described.

DESCRIPTION

FIG. 1 is a top-front-left side perspective view of an electric bicycle embodying my new design;
FIG. 2 is a bottom-rear-right side perspective view thereof;
FIG. 3 is a left side elevation view thereof;
FIG. 4 is a right side elevation view thereof;
FIG. 5 is a front elevation view thereof;
FIG. 6 is a rear elevation view thereof;
FIG. 7 is a top plan view thereof; and,
FIG. 8 is a bottom plan view thereof.
